[57] **CLAIM**

The ornamental design for the flashlight, as shown and described.

DESCRIPTION

FIG. 1 is a oblique view of a first embodiment of the invention;
FIG. 2 is a side elevation view of the invention;
FIG. 3 is a side elevation view of the invention taken at a right angle to that shown in FIG. 2;
FIG. 4 is a side elevation view of the invention from a side opposite that shown in FIG. 2;
FIG. 5 is a front elevational view of the invention;
FIG. 6 is a rear elevational view of the invention;
FIG. 7 is an oblique view of a second embodiment of the invention;
FIG. 8 is a side elevation view of the invention;
FIG. 9 is a side elevation view of the invention taken at a right angle to that shown in FIG. 8;
FIG. 10 is a side elevation view of the invention from a side opposite that shown in FIG. 8;
FIG. 11 is a front elevational view of the invention;
FIG. 12 is a rear elevational view of the invention;
FIG. 13 is an oblique view of a third embodiment of the invention;
FIG. 14 is a side elevation view of the invention;
FIG. 15 is a side elevation view of the invention taken at a right angle to that shown in FIG. 14;
FIG. 16 is a side elevation view of the invention from a side opposite that shown in FIG. 14;
FIG. 17 is a front elevational view of the invention;
FIG. 18 is a rear elevational view of the invention; and,
FIG. 19 is a perspective view of the flashlight head common to each of the embodiments shown in FIGS. 1-18.
